PEPPER MILL OR THE LIKE

John W. Bentley, Berkeley, Calif.

Application March 24, 1953, Serial No. 24,189

Term of patent 14 years

(Cl. D44—22)

To all whom it may concern:

Be it known that I, John W. Bentley, a citizen of the United States, residing in Berkeley, county of Alameda, and State of California, have invented a new, original, and ornamental Design for a Pepper Mill or the like, of which the following is a specification, reference being had to the accompanying drawing, forming part hereof, in which:

Figure 1 is a perspective view of a pepper mill or the like, showing my new design;

Figure 2 is a side elevational view thereof, the pepper mill or the like being identical and symmetrical from all sides; and

Figure 3 is a top plan view.

I claim:

The ornamental design for a pepper mill or the like, substantially as shown and described.

JOHN W. BENTLEY.
